UNITED STATES PATENT OFFICE

2,263,530

YARN FEEDING MEANS FOR KNITTING MACHINES

Oscar Fregeolle, Central Falls, R. I., assignor to
Hemphill Company, Central Falls, R. I., a corporation of Massachusetts

Original application June 25, 1940, Serial No.
342,323. Divided and this application September 6, 1940, Serial No. 355,632

4 Claims. (Cl. 66—131)

This case concerns an invention in feeding yarns to needles of knitting machines, more especially for feeding yarns such as elastic yarns to latch needles of circular, independent needle knitting machines. This case is a division of applicant's co-pending application Serial #342,323, filed June 25, 1940.

In the figures of drawings:

Fig. 1 is an elevation showing certain representative parts of a typical hosiery machine and the manner in which feeding means is operated thereon;

Fig. 2 is an isometric view showing the novel feeding means as it is employed to feed a yarn to hooks of selected needles;

Fig. 3 is a section through the feeding means showing its relative cooperation with passing needles and sinkers;

Fig. 4 is a section, greatly enlarged, taken horizontally through the feeding means showing the manner in which yarn is guided into close proximity to the shanks of passing needles; and

Fig. 5 is a view similar to Fig. 4, showing the feeding as viewed from another angle.

In feeding yarns such as an elastic yarn, either covered or uncovered, that yarn should be introduced very close to the shanks of needles so to make certain that the same becomes engaged in the hooks of those needles which are intended to take it to the exclusion of its being caught by others. To this end a close feeding mechanism as herein described and claimed is to be employed. While the same is especially useful in feeding elastic yarns as above mentioned, it is by no means limited to that use only, but is of universal application. While described with respect to an independent needle knitting machine having latch needles and of circular type, the invention applies to other machines and other types of needles, and is to be employed wherever the same serves effectively in overcoming the difficulties above referred to.

Referring to Fig. 1 certain parts of a typical hosiery machine of circular type are shown including a so-called circular base 1, cylinder 2, sinker assembly 3 and a carrier ring 4. This carrier ring is to be pivoted at 5 on a post 6 and in an extension generally indicated by numeral 7, has operatively mounted a plurality of yarn feeding fingers or guides which function at the so-called main feeding station of the machine. These are employed to feed the usual yarns and are actuated through mechanism extending down through the yarn lever box 8, this mechanism and its operation being well known to those

skilled in the art and a description thereof being available in United States Patent #933,443. In the cylinder 2 needles generally indicated by numeral 9 are adapted to be independently actuated by certain cams and selecting mechanism not shown or described in detail in this case. Sinkers 10 are likewise operatively controlled by the usual mechanism in a sinker cam cap which is a part of the sinker assembly 3.

At a separate point spaced from the main feeding station or mouthpiece, a vertically disposed yarn feeding finger 11 is fixed to one end of an angularly bent lever 12 which is in turn pivoted on the spindle 5. This lever 12 has two extensions, one more or less horizontally disposed and indicated at 13 and a second indicated by numeral 14, but disposed in substantially a vertical direction. A spring 15 normally tends to draw lever 12 and all attached parts into the position shown in Fig. 1. That is the position in which finger 11 is adapted to feed its yarn (elastic or other yarn) to certain of the needles. When it is desired to withdraw a yarn fed by the lever 11, link 16 is pulled downwardly by mechanism controlled by certain appropriate cams on the machine (not shown), this control being what is generally termed a master control and operable for initially introducing and finally withdrawing the yarn fed to the finger 11. If feeding is to be periodically interrupted as when feeding an elastic yarn to spaced courses only, lever 17 fixed to a spindle or shaft 18 rotatable in bracket 19, is caused to press against the side of depending arm 14 thereby to swing the lever 12 and do what is normally referred to as "jump" the finger 11 from feeding position throughout certain desired courses. A second lever 20 is also fixed to the spindle 18 and is controlled by a tappet 21 which derives a reciprocatory movement from certain cams (not shown). The stop 22 may be adjusted and limits the swing of the finger 11 to a particular feeding position. When the arm 12 swings to the position of Fig. 1 arm 14 contacts the stop 22.

Now referring to Figs. 2-5, the construction of the feeding means itself is illustrated in greater detail. The finger 11 is shown greatly enlarged in these views and has a lower depending portion 23 of greatly reduced thickness and an opening 24 through which the yarn *y* is threaded. When in lower position as illustrated in Fig. 3, this yarn feeding opening or eyelet is at a level slightly above the tops of nibs of sinkers but below hooks of passing needles, that is, such needles as are to take the particular yarn fed by this

finger 11. Normally in feeding elastic yarn, spaced needles only take the same and thus certain selection is employed to raise those needles while others remain in a lower elevation, preferably considerably lower or at least low enough so that hooks thereof are well below the feeding range of the yarn. As shown in Figs. 2, 4 and 5, the reduced end 23 of the finger 11 is built up or has a projection or boss 25 which serves to push the yarn outwardly against the shanks of passing needles and beneath hooks thereof. This projection 25 is beveled at each side as shown and the hooks of selected needles pass above the top beveled edge 26 of the boss, but closer to the reduced end 23 of the finger than the outer surface 27 of the boss, which surface is parallel to the shanks of needles. As can be seen from an inspection of Figs. 4 and 5, the yarn can not fail to be taken within needle hooks since it is guided directly beneath them and needles are not drawn downwardly so that the hooks engage the yarn until they have passed the boss 25. This assures that upon introduction of the yarn *y* to be taken by a particular needle of a group, that needle will not fail to be the first to engage the yarn. Otherwise, with the so-called jumping finger construction, and without special needle division at the start of taking the yarn, it might vary over several needles as it was introduced. In machines of this type it is not generally practicable to move the finger to and from an active position and simultaneously interrupt the selection of needles. If needles are to take the yarn such as an elastic yarn in knitting a stocking top, those needles are selected throughout the entire knitting of the top. The yarn may be fed at spaced courses only by periodically inserting and withdrawing it to and from feeding position. The mechanism herein described serves to assure introduction of and withdrawal of the yarn at a particular needle or wale.

The needle hooks may actually rub against the side of the extension 23 nearest thereto, or, in the event a needle passes at an extremely low level or the finger 11 is not moved down quite as far as it should be, hooks will merely contact the front beveled edge of the boss 25 and pass without doing any damage.

The invention has been described with respect to a preferred form thereof merely by way of example and this description is not to be interpreted in a limiting sense. Certain modifications will occur to those skilled in the art and may be adopted without departing from the general spirit and teaching of the invention. The invention is defined in the appended claims.

I claim:

1. In a knitting machine yarn feeding means including a finger having an opening therein through which a yarn is to be threaded and from which it emerges to be taken in needle hooks of the machine, a projection on said finger adjacent said opening through which the yarn is threaded, having beveled surfaces for guiding the yarn into close relationship with passing needles, but so constructed and positioned as to project beneath but to avoid contact with needle hooks.
2. In a knitting machine the combination of independently operated needles having hooks and latches and a shank portion between said hooks and latches, yarn feeding means movable to and from feeding position with respect to needles and having adjacent its lower end an opening through which a yarn is to be threaded and from which it emerges to be taken by the needles, a projection or boss having beveled surfaces leading to an outermost flat surface, said boss being so positioned and constructed as to push a feeding yarn outwardly beneath needle hooks and adjacent the shank portions thereof beneath the hooks, but so positioned as to allow needle hooks to pass above while needle latches pass beneath.
3. Yarn feeding means for knitting machines of the type described including an elongated finger of generally rectangular section, an opening at one end through which a yarn is to be threaded and from which it emerges to be taken by the knitting machine needles, and a boss adjacent said opening and at substantially the same level as the opening, said boss having beveled surfaces leading from one face of the finger and outwardly to a generally flat surface parallel to the said face of the finger, said flat surface being in a plane substantially parallel to but spaced outwardly from the surface of the finger from which the yarn would emerge.
4. A yarn feeding means for a knitting machine including a vertically operable finger of rectangular cross-section and having a flat surface from which projects a boss, an opening through which a yarn is to be threaded adjacent the boss and at substantially the same height as the center of the boss and from which it would emerge to be taken by knitting machine needles, said boss having an outermost, flat surface parallel to the surface of the finger and beveled sides leading back from said outer flat surface to the surface of the finger from which a feeding yarn would emerge.

OSCAR FREGEOLLE.
